FLUORESCENT LAMP FIXTURE

Charles E. Winebrenner, Garrett, Ind.

Application May 15, 1950, Serial No. 9,946

Term of patent 14 years

(Cl. D48—23)

To all whom it may concern:

Be it known that I, Charles E. Winebrenner, a citizen of the United States, residing at Garrett, in the county of DeKalb and State of Indiana, have invented a new, original, and ornamental Design for a Fluorescent Lamp Fixture, of which the following is a specification, reference being had to the accompanying drawing, forming part thereof.

Fig. 1 is a bottom perspective view of a fluorescent lamp fixture showing my new design,

Fig. 2 is a bottom view thereof, and

Fig. 3 is a cross sectional view of the same taken on the line 3—3 of Figure 1.

I claim:

The ornamental design for a fluorescent lamp fixture, as shown.

CHARLES E. WINEBRENNER.
